SEELEY C. GULICK, OF CHAMPAIGN, ILLINOIS

FUEL FEEDING DEVICE

Application filed June 5, 1929. Serial No. 368,696.

This invention relates to fuel feeding devices, and more particularly to a device for supplying fuel from the tank of a motor vehicle to the carburetor of the engine.

The present types of vacuum tanks for supplying fuel to motor vehicle carburetors are open to several objections. For one thing, the parts of the device are relatively light and are readily subject to derangement so as to interfere with their operation. Furthermore, vacuum tanks are provided with snap-over valves one of which is adapted to connect the suction chamber of the tank to the intake manifold when the vacuum tank is refilled, thus supplying uncarbureted air to the intake manifold which, under ordinary conditions, does not materially affect the operation of the engine, but does cause a loss of power to a noticeable extent when the engine is picking up speed after the vehicle has been started from a standstill.

A number of motor vehicles are now equipped with positive pumps for transferring fuel from a motor vehicle tank to the carburetor thereof, but such devices also have been found to possess disadvantages. For example, a pump of this character must operate to supply fuel at a sufficient rate to satisfy the maximum demands of the engine, and under a majority of conditions, the motor pumps fuel in excess of the actual rate of consumption by the engine, and this excess flow must be compensated for in some manner.

Many of the power driven pumps now in use for the purpose stated are provided with a pump plunger or similar pumping element and actuating means usually in the nature of a cam drive, and the drive means and the pump element are usually mechanically connected to each other through the medium of a compression spring which possesses sufficient tension to transmit power to the pumping elements, but which is adapted to be compressed upon the building up of a back pressure against the pumping element so as to prevent the transmission of power to the pumping element when there is an accumulation of excess fuel being pumped. As is well known, it is difficult to provide springs of this character which are more or less constantly

compressed and expanded owing to the fact that the metal of the springs crystallizes, thus causing the springs to break.

In a copending application Serial No. 292,310, filed July 12th, 1928, I have disclosed a fuel supply system for oil burners having novel means for taking care of the fuel pumped in excess of the demands of the burner. The present invention embodies the same broad principle, but is particularly adapted for use in connection with motor vehicles.

An important object of the present invention is to provide a simple and substantial mechanism for the purpose stated, wherein there is a complete absence of delicate moving parts whereby the device is adapted to operate over long periods of time without derangement or breakage of parts.

A further object is to provide novel means for compensating for the excess fuel pumped without the use of springs or other take-up means.

A further object is to provide a device of the character referred to wherein the operating parts for transmitting the pumping power are of such character as to render lubrication thereof unnecessary over long periods of time, novel means being provided for retaining a body of lubricant in intimate contact with such working parts.

A further object is to provide a pumping device having an auxiliary fuel tank associated therewith from which the fuel is adapted to flow to the carburetor by gravity and to provide means for returning excess fuel from the auxiliary tank to the intake side of the pump to prevent the latter from drawing additional fuel from the main tank except as the requirements of the carburetor demand it.

Other objects and advantages of the invention will become apparent during the course of the following description.

In the drawings I have shown one embodiment of the invention. In this showing,

Figure 1 is a side elevation, parts being shown in section,

Figure 2 is a plan view,

100

Figure 3 is a detail perspective view of the pumping element and associated parts,

Figure 4 is a central vertical sectional view,

5 Figure 5 is a section on line 5—5 of Figure 1, parts being shown in elevation,

Figure 6 is a detail sectional view of the three-way valve means for taking care of excess fuel, parts being shown in elevation, and,

10 Figure 7 is a detail perspective view of a bearing element and lock nut therefor.

Referring to the drawings, the numeral 10 designates an auxiliary fuel tank which is preferably formed of sheet metal and is provided in its bottom with a clean-out plug 11. The upper end of the tank 10 is provided with an annular flange 12 adapted to be attached by screws or other fastening elements 13 to a support 14, a gasket 15 preferably being arranged between the flange 12 and the support 14.

The tank 10 is provided with a hollow lateral extension 16, which may be formed integral therewith or brazed thereto, and the extension 16 is provided with an integral vertical tubular member 17, closed at its lower end by a plug 18. The tubular member 17 is provided in its upper portion with a valve seat 19, for a purpose to be described.

30 A float 20 is arranged in the tank 10 and is carried by a lever 21 pivotally connected intermediate its ends as at 22 to the extension 16. The outer end of the lever is provided with a valve 23 adapted to engage the seat 19 when the float 20 moves downwardly to a predetermined position.

The upper end of the tubular member 17 is connected to one branch 24 of a three-way connection 25. A second branch of the connection 25 communicates with a pipe 26, while the third branch of the connection communicates with another pipe 27. The lower end of the pipe 26 is connected to a valve casing 28 in which is arranged a ball valve 29 governing the flow of fuel through an opening 30, and this opening communicates with a pipe 31 which leads to the main fuel tank of the vehicle.

Referring to Figures 1 and 4, the numeral 32 designates a plurality of upstanding posts secured at their lower ends to the support 14 by screws or other fastening elements 33. A plate 34 is secured to the upper ends of the posts 32 by screws or other fastening elements 35, and the lower face of the plate 34 is recessed as at 36 to form a pumping chamber.

60 A diaphragm 37 is mounted against the lower face of the plate 34 and is secured thereto by a clamping ring 38 having screws or other fastening elements 39 passing therethrough and threaded in the plate 34. The diaphragm is provided with a central depending stem 40, bifurcated at its lower end as

at 41, and secured to the diaphragm by a screw 42.

A power transmission casing 41' is mounted on the upper face of the support 14 and is secured thereto by screws or the like 43 as shown in Figure 4. One wall of the casing 42 is preferably provided with a detachable cover plate 42' which is removable to permit access to the interior of the casing. The casing 42 is preferably rectangular in cross section, as shown in Figure 5, and is provided in opposite side walls with threaded openings 43' receiving threaded bearings 44 having eccentric bearing openings 45 in their inner ends. The bearings are adapted to be secured in adjusted positions by means of jam nuts 45'.

75 A shaft 46 is arranged in the casing 42 and has its ends mounted in the bearings 44. The shaft 46 is provided adjacent one end with an eccentric 47 operable in a bearing 48 carried by an upwardly extending stem 49'. This stem is secured by suitable fastening elements 49 to an elongated shank 50, as clearly shown in Figure 3. A screw 51 extends through a slot 52 formed in the upper end of the shank 50, and is threaded into a connecting member 53. The upper end of the connecting member is mounted between the bifurcated ends of the stem 40 and is pivotally connected thereto as at 54.

85 A light motor 55 is mounted on the support 14 by suitable bolts 56 and has its armature shaft 57 projecting through an opening 58 formed in one of the side walls of the casing 100 42. The end of the armature shaft is provided with a worm 59 meshing with a worm wheel 60 rigidly secured to the shaft 46.

90 As shown in Figure 6, the plate 34 is provided with a passage 61 communicating with the pump chamber 36. A valve body 62 is threaded on the plate 34 and is provided with a passage 63 communicating with the passage 61. A ball valve 64 is mounted in the passage 63 and is adapted to seat against the upper end of a reduced passage 65. The valve body 62 is connected at its lower end to the pipe 27 to receive fuel therefrom in a manner to be described.

95 Another valve body 66 is threaded in the top of the plate 34 and is provided in its lower end with a reduced passage 67 communicating with the passage 61. A ball valve 65 is adapted to control communication through the passage 67. The valve body 66 is connected above the ball valve 65 to an outlet pipe 69.

115 The pipe 69 extends across the plate 34, and thence downwardly, as shown in Figures 1 and 2, and the lower end of the pipe is connected to an elbow 70 which communicates with the tank 10 to supply fuel thereto. From the tank 10, fuel is adapted to flow by gravity to the carburetor through an outlet pipe 71, and this pipe is preferably provided 125 130

with a manually operable valve 72. The tank 10 is vented through an opening 73 formed in the support 14, and a vent pipe 74 is preferably connected at its lower end to the opening 72, and has its end turned downwardly as shown in Figure 4 to prevent dust and foreign matter from finding its way into the tank 10.

The operation of the device is as follows:

As previously stated, the pipe 31 is connected to the main source of fuel supply of the vehicle. The motor 55 is preferably connected to the ignition switch of the engine so as to operate only when the engine is running. Rotation of the motor obviously drives the worm 59 which, in turn, drives the worm wheel so as to rotate the shaft 46 and cam 49. The cam, rotating in the bearing 48, transmits reciprocating movement to the shank 50 and the parts connected thereto, and this movement, in turn, is transmitted to the diaphragm 37 to effect the desired pumping action. Referring to Figure 6, it will be noted that downward movement of the diaphragm creates a partial vacuum in the chamber 36, which seats the valve 65 and unseats the valve 64, and thus fuel will be drawn into the chamber 36 from the pipe 27. Upon upward movement of the diaphragm 37, a pressure will be created in the chamber 36, thus seating the valve 64 and unseating the valve 65 to discharge fuel through the pipe 69.

The fuel thus pumped is discharged by the pipe 69 into the tank 10, through the elbow 70, and fuel will flow by gravity to the carbureter through the pipe 71, the tank 10 being vented through the pipe 74. As stated, pumping means must be provided which will take care of the maximum demands of the engine, and under most conditions, the amount of fuel pumped to the tank 10 will exceed the amount flowing from the tank to the carbureter. Novel means is provided for taking care of the excess fuel thus pumped without the provision of spring take-up means or the like.

Referring to Figure 4, it will be noted that when the device is first placed in operation, the level of the fuel in the tank will be such that the float 20 will move downwardly, thus closing the valve 23 and shutting off communication between the tank and the three-way connection 25. As the height of the fuel rises, the float will rise correspondingly until the valve 23 becomes partially unseated, at which time, fuel can flow from the tank 10 to the three-way connection 25, and thence into the pipe 27.

Under the conditions stated, it will be apparent that the pump will draw part of its supply from the main tank and part from the tank 10, the proportionate amounts supplied from the two sources to the three-way connection 25 depending upon the height of the fuel in the tank 10, and the consequent

degree to which the valve 23 is opened. When the rate at which the fuel is pumped greatly exceeds the rate of consumption, the valve 23 obviously will open to a greater extent where by the greater ratio of fuel drawn into the pump chamber 36 will be provided from the tank 10 and it will be apparent that under all circumstances, the amount of fuel drawn from the main supply tank will correspond exactly to the amount of fuel being consumed by the engine.

It has been found that a very light drive motor may be provided since the consumption of fuel by an engine takes place slowly, thus permitting the use of reduction gearing with the pump drive means. In actual practice, it has been found that a motor may be employed which does not consume any more current than the usual tail or dash light of the vehicle.

The casing 42 serves as a reservoir for lubricant, which is maintained below the level of the opening 58. The jam nuts 55 serve to prevent leakage of oil through the openings 43', and accordingly it is unnecessary to lubricate the drive means, except at rare intervals. The worm wheel 60 moves through the body of the lubricant and carries it to the worm 59 to lubricate the latter.

The bearings 44 are provided to permit taking up wear between the worm wheel 60 and the driving worm 59. It will be apparent that by loosening the jam nuts 45', the bearings 44 may be slightly rotated, and eccentricity of the openings 45 will cause the shaft 46, and the worm wheel 60 to be slightly elevated. Thus it will be apparent that excess play between the worm and worm wheel may be taken up whenever desired. The vertical adjustment of the shaft 46 may be compensated for in the driving connections to the diaphragm by loosening the screw 51 when the bearings 44 are adjusted, and then by tightening the screw 51 after the desired adjustment has been obtained.

From the foregoing it will be apparent that the present device provides novel means for supplying fuel to an internal combustion engine wherein the rate of withdrawal of fuel from the main tank exactly corresponds to the rate of consumption of fuel by the engine, and it is unnecessary to provide any spring take-up means between the source of power and the pumping element, as would be necessary if the pumping of excess fuel to the carbureter should create back pressure on the diaphragm 37. The device is characterized by an absence of fragile parts, and is adapted to operate over long periods of time without any attention whatever either as to lubrication or adjustments.

It is to be understood that the form of the invention herewith shown and described is to be taken as a preferred example of the same, and that various changes in the shape, size

and arrangement of parts may be resorted to without departing from the spirit of the invention or the scope of the subjoined claims.

I claim:

- 5 1. A fuel feeding device comprising a tank vented to the atmosphere, a discharge pipe connected to said tank near the bottom thereof, a pump including a pump chamber and a flexible diaphragm, inlet and outlet pipes connected to said pump chamber, said pipes being connected respectively to a source of fuel supply and to said tank, a transmission casing, a worm wheel mounted in said casing, driving connections between said worm wheel and said diaphragm, said transmission casing being provided with an opening spaced from the bottom thereof, a shaft rotatable in said opening and provided in said casing with a worm meshing with said worm wheel,
- 10 20 a shaft carrying said worm wheel, bearing means rotatably supporting said last named shaft and operative to vary the distance thereof from said worm wheel, said casing being adapted to contain a lubricant in the bottom thereof and means for driving said first named shaft.
- 15 23

2. A fuel feeding device comprising a horizontal support having a vent opening therethrough, an open topped tank having a horizontal flange at its upper end secured against the lower face of said support, a discharge pipe connected to said tank near the bottom thereof, a pump carried by said support and spaced thereabove, inlet and outlet pipes connected to said pump, said pipes being connected respectively to a source of fuel supply and to said tank, a transmission casing mounted between said pump and said support and carried by the latter, transmission gearing arranged in said casing near the bottom thereof and operatively connected to said pump, said casing being adapted to contain lubricant in the bottom thereof, and means arranged externally of said casing for driving said gearing.
- 30 35 40 45

In testimony whereof I affix my signature.
SEELEY C. GULICK.
